US0D1015030S

(12) **United States Design Patent** (10) Patent No.: **US D1,015,030 S**
(45) Date of Patent: ** Feb. 20, 2024

(54) **RETAIL FIXTURE GROUP**

(71) Applicant: **Apple Inc.**, Cupertino, CA (US)

(72) Inventors: **Alice Marlin Brugger**, San Francisco, CA (US); **Manuel Dejesus**, San Francisco, CA (US); **Joshua Robert Edwards**, Santa Cruz, CA (US); **Jean-Marc Gady**, Los Altos, CA (US); **Wesley Bryan Hamm**, San Francisco, CA (US); **Russell John Kaaihue Heirakuji**, Cupertino, CA (US); **Allison Inouye**, San Francisco, CA (US); **Moritz Wilsberg**, Rheinbreitbach (DE)

(73) Assignee: **Apple Inc.**, Cupertino, CA (US)

(**) Term: **15 Years**

(21) Appl. No.: **29/829,021**

(22) Filed: **Mar. 2, 2022**
